CLAIM

The ornamental design for a die for game, as shown and described.

DESCRIPTION

FIG. 1 is a perspective view of the die for game; FIG. 2 is another perspective view of the die for game; FIG. 3 is another perspective view of the die for game; FIG. 4 is another perspective view of the die for game; FIG. 5 is another perspective view of the die for game; FIG. 6 is a side view of the die for game; FIG. 7 is another side view of the die for game; FIG. 8 is another side view of the die for game; and, FIG. 9 is another side view of the die for game.

The evenly spaced broken lines shown in the drawings depict portions of the die for game that form no part of the claimed design. The dot-dash-dot broken lines depict boundary lines of the claim and form no part thereof.
